UNITED STATES PATENT OFFICE.

GEORGE SHIPMAN, OF WEST BRIDGEWATER, MASSACHUSETTS.

EYELETING-MACHINE.

SPECIFICATION forming part of Letters Patent No. 288,373, dated November 13, 1883.

Application filed June 7, 1883. (No model.)

To all whom it may concern:

Be it known that I, GEORGE SHIPMAN, of West Bridgewater, in the county of Plymouth, in the State of Massachusetts, have invented 5 certain new and useful Improvements in Eyeletting Machines, of which the following is a specification.

My invention relates to that class of eyeletting-machines in which the eyelet-reservoir and eyelet-road automatically retire at each motion of the machine, and has for its object to so construct and arrange the road-sustaining device that when the road retreats it falls, but maintains practically its parallelism, and in falling 10 enlarges the clearance between the road and the upper arm of the machine, thus allowing broader objects to be inserted for the action of the eyeletting device. I attain this object by the mechanism illustrated in the accompanying 15 drawings, in which—

Figure 1 is a side elevation of my machine, and Fig. 2 is a plan of the same.

A B represents the base and frame of the machine, which may be cast in a single piece, 25 of the form shown in the drawings.

To the lower end, C, of the upper arm, B, I attach the anvil C', from the center of which the guide-pin C² projects. (See Fig. 1.)

At the extremity A' of the lower arm of the 30 frame I insert a piston, E', said piston having at its upper end an eyelet-carrying point, E, said point E being a piston within the piston E', and arranged with a spring, so that unless forcibly depressed it projects, as shown in Fig. 35 1; but when the said eyelet-receiving point E has received its eyelet, and has been forced upward to come in contact with the guide-pin C², it will be forced downward into the piston E³, so that the part E³ of the piston will force 40 the eyelet against the anvil C', and thus rivet it into the work.

E' is a link pivoted to the piston E' at e, and to the lever H at e'. This lever H has a fulcrum at H', which projects from the frame A. 45 The rear end, H², of the lever H is drawn upward by the spring H³, the upper end of which is attached to a projection, H⁴, which extends from the frame A B. (See Fig. 1.)

All of the above-described parts are in common use in eyeletting-machines.

I now proceed to describe my invention, which consists in the method of suspending the eyelet-road D.

K is a link pivoted on the fulcrum H' of the

lever H, the upper end being pivoted at K² to 55 the eyelet-road D D'.

M, Fig. 1, is a second link, parallel with the first-described link K, and pivoted to the frame of the machine at M² and to the eyelet-road 60 at M'.

K' is a pin projecting from the lever H through an opening in the link K, the pin and opening being so adjusted to each other that the lever H may have at that point considerable motion before the said pin K' comes in 65 contact with the upper part of the opening in the link K. Thus the lever may, acting through the link E², throw the piston E' E³ and the eyelet-receiving point E upward sufficiently to receive an eyelet before the pin K' begins to act on the link K. When it does begin to act on the link K, it will throw the said link over in the direction indicated by the arrow S. This will throw the eyelet-road D D' backward and downward; but as the road D D' has 75 a second guiding-link, M, it must fall without losing its parallelism. This falling motion imparted to the road D D' enlarges the space between it and the upper arm, B, of the frame, so as to admit of the insertion of broader articles to be acted upon than otherwise could be.

L² is a boss on the link K, through which a set-screw, L', passes.

L is a corresponding projection from the frame, and serves as a buttress for the point of the screw L'. This device admits of limiting the forward motion of the road to any desired point. R R' is a similar limiting device for the motion of the lever H.

P, Fig. 1, is a strap of thin metal, fastened 90 to bosses P P' on the frame A, and, being outside of the lever K, serve to cause it and the road D D' to move in a vertical plane.

H⁵, Fig. 1, is a link which serves to connect the lever H² with the foot-treadle or other 95 means for communicating motion to the machine.

I claim—

In an eyeletting-machine, the combination of the eyelet-road D D' and the link M with the 100 link K and lever H H², all operating together substantially as described, and for the purpose set forth.

GEORGE SHIPMAN.
